United States Patent Office

Des. 203,361
Patented Dec. 28, 1965

203,361

BOTTLE CAP

John F. Becker, Vineland, N.J., assignor to Wheaton Glass Company, Millville, N.J., a corporation of New Jersey

Filed Dec. 3, 1964, Ser. No. 82,898

Term of patent 14 years

(Cl. D58—26)

Fig. 1

Fig. 2

Fig. 3

Fig. 4

Fig. 5

FIG. 1 is a perspective view of a bottle cap showing my new design, the portions shown in broken lines being for illustrative purposes only;

FIG. 2 is a top plan view thereof;

FIG. 3 is a bottom plan view thereof;

FIG. 4 is a side elevation thereof; and

FIG. 5 is an end elevation thereof.

I claim:

The ornamental design for a bottle cap, substantially as shown and described.
